UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

MACHINE FOR OPERATING UPON BOOT AND SHOE SOLES.

1,174,042.

Specification of Letters Patent.

Patented Mar. 7, 1916.

Application filed March 4, 1912. Serial No. 681,335.

To all whom it may concern:

Be it known that I, ARTHUR BATES, a subject of the King of Great Britain, residing at Leicester, in the county of Leicestershire, England, have invented certain new and useful Improvements in Machines for Operating Upon Boot and Shoe Soles; and I do hereby declare the following to be a full, clear, and exact description of the invention, such as will enable others skilled in the art to which it appertains to make and use the same.

The present invention relates to machines for operating upon boots and shoes, and more particularly to machines for operating upon the soles of boots and shoes which comprise a rotary tool and mechanism for actuating the tool.

The object of the present invention is to provide an improved and efficient machine of the character described for performing various operations upon the shoe sole which operates over all portions of the sole without the necessity of altering the lateral inclination of the shoe as presented to the machine.

With this object in view, a feature of the invention consists in the provision of a rotary tool, a supporting shaft for the tool, and means for tipping the tool alternately in opposite directions to enable the tool to cover all portions of the sole as the shoe is passed across the tool.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention, Figure 1 represents a plan view, partly in section, of a machine embodying the several features of the invention; Fig. 2 is a view similar to Fig. 1 illustrating a modified construction; and Fig. 3 is a section upon the line 3—3 of Fig. 2 looking in the direction of the arrows.

The machine shown in the illustrated embodiment of the invention is provided with a roll for operating upon the soles of boots and shoes and is employed principally for burnishing the surface of the soles. The

roll is tipped laterally and caused to assume different angles of inclination relative to the shaft by suitable means which, in the simplest and most efficient form of the invention yet devised, comprises a sleeve provided with an oblique bore to receive the shaft and interposed between the roll and shaft. The sleeve or bushing supports the roll in an oblique position relative to the shaft, and when the sleeve and roll are rotated relatively to one another a wabbling or tipping movement in opposite directions is imparted to the roll. In the illustrated embodiment of the invention the sleeve is constructed and arranged to oscillate the roll about an axis coinciding with the median line of the roll, thus imparting equal tipping movements in opposite directions to the roll.

The roll is indicated at 1, and is provided with a concave periphery in order to enable it to conform more closely to the surface of the sole in cross section. The roll is supported upon a drive shaft 2 journaled at its opposite ends in bearings 3 and 4 and actuated by a drive pulley 6 keyed thereto. In order to lock the roll against rotation relatively to the shaft, and to allow a free tipping of the roll in any direction, a universal joint connection is provided between the roll and shaft. To this end a collar 10 is secured to the shaft 2 and is provided with a pair of projecting lugs 11 as shown clearly in Fig. 1. A second collar 12 is loosely supported upon the shaft 2 and is provided with recesses formed in one face 90 to receive the lugs 11 and with a pair of projecting lugs 13 located upon its opposite face and disposed at right angles to the lugs 11. The lugs 13 are received in cooperating recesses formed on one end of the roll 1, thus locking the roll to the driving shaft 2 and at the same time allowing the roll to tip freely in any direction. The tipping or wabbling movements are imparted to the roll by a sleeve 15 interposed between the roll and shaft and connected to a drive pulley 16 through a sleeve 17. The sleeve 15 is cylindrical in form and is provided with an oblique bore to receive the shaft 2. The roll is secured against longitudinal movement relative to the sleeve 15 by an annular shouldered ring 20 fastened to the roll by a plurality of bolts 22 and coöoperating

with a flange 23 formed upon the sleeve. The roll is driven at a higher speed than the eccentric sleeve 15, thus causing the movement of the roll through varying angles of 5 inclination to take place smoothly and evenly, bringing the roll into contact with all portions of the shoe sole to rub and polish the same without marring. Although tipping movements of equal amounts are imparted to opposite ends of the roll, in the 10 present invention, it is to be understood that these movements can be varied as desired without departing from the spirit and scope of the invention.

15 When the roll is used for burnishing it is desirable that it be heated artificially, and this is accomplished simply and efficiently by the employment of friction material contacting with the surface of the roll. To this 20 end a pad 30 of felt or other friction material is secured in a holder 31, and is arranged to press yieldingly against the surface of the roll. In order to retain this pad in engagement with the roll in whatever position the roll may be, a support 32 is slid- 25 ingly mounted in a recess formed in the frame of the machine, and is connected to the holder 31 by a ball and socket joint indicated at 33. The support 32 is normally 30 pressed out by a coiled spring 34 received in the recess and interposed between the support and a threaded cap nut 35 closing the end of the recess.

In the modified form of construction illustrated in Figs. 2 and 3 the roll is indicated at 36 and is supported upon a drive shaft 37 journaled at its opposite ends in the machine frame. The roll is provided upon its interior with a spider 40 forming a hub for 40 the roll and connected to the shaft by means of a key 41 engaging with a coöperating key-way formed in the spider. The key 41 is swiveled in a transverse slot formed in the shaft 37, and is provided with a T-shaped 45 head 42 engaging with the spider. It will be noted from an inspection of Figs. 2 and 3 that there is sufficient distance between the sides and top of the key and key-way to allow all necessary movement of the roll relative to the shaft without cramping the key 50 in its bearings. Tipping movements are imparted to the roll by a sleeve 44 bored obliquely and received in one end of the roll. The roll is secured against longitudinal 55 movement relative to the sleeve by an annular ring 45 secured to the spider 40 and co-operating with a flange 46 formed upon the sleeve. Artificial heat is applied to the roll by a gas burner indicated at 50, which projects within the roll and is secured in a bracket 51.

The operation of the machine may be briefly stated as follows: The operator presents the shoe to the rapidly rotating roll, 60 and then manipulates it to cause the shoe

sole to traverse longitudinally of the face of the roll. As the shoe is removed across the roll, the roll rubs and polishes each successive portion of the sole, and the tipping movements imparted to it alternately in opposite directions enable the roll to accommodate itself to the varying curvature of the shoe sole in cross section without making it necessary for the operator to alter the lateral inclination of the shoe.

70 While it is preferred to employ the specific construction and arrangement of parts shown and described, it will be understood that this construction and arrangement is not essential except so far as specified in the claims, and may be changed or modified without departing from the broader features of the invention.

75 The invention having been described, what is claimed is:—

80 1. A machine for operating upon boot and shoe soles, having, in combination, a rotary tool, a shaft for the tool, and means for causing the tool when rotated to assume different angles of inclination relative to the 85 shaft, substantially as described.

90 2. A machine for operating upon boot and shoe soles, having in combination, an elongated substantially cylindrical tool having its periphery adapted to operate upon a 95 shoe sole, a shaft for the tool, and means for supporting the tool with its axis of rotation arranged obliquely to the axis of the shaft, substantially as described.

100 3. A machine for operating upon boot and shoe soles, having, in combination, a tool, a supporting shaft for the tool, an oblique sleeve interposed between the tool and shaft, and means for securing a relative rotation of the sleeve and tool, substantially 105 as described.

110 4. A machine for operating upon boot and shoe soles, having, in combination, a rotary tool, a supporting shaft for the tool, an oblique sleeve interposed between the tool and shaft, and means for rotating the tool at a higher rate of speed than the sleeve, substantially as described.

115 5. A machine for operating upon boot and shoe soles, having, in combination, a rotary tool, a supporting shaft for the tool, and means for tipping the tool alternately in opposite directions to enable the tool to cover all portions of the shoe sole as the shoe is passed across the tool, substantially as described.

120 6. A machine for operating upon boot and shoe soles, having, in combination, a rotary tool, a driving shaft, driving connections between the shaft and the tool to allow a free 125 lateral movement of the tool relative to the shaft, and means for imparting tipping movements to the tool, substantially as described.

125 7. A machine for operating upon boot and

shoe soles, having, in combination, a rotary tool, a supporting shaft for the tool, and a cylindrical sleeve interposed between the tool and shaft and provided with an oblique bore to receive the shaft, substantially as described.

8. A machine for operating upon boot and shoe soles, having, in combination, a roll, a supporting shaft for the roll, means for imparting tipping movements to the roll, a friction pad, and means for pressing the friction pad yieldingly against the surface of the roll in all positions of the roll, substantially as described.

10 9. A machine for operating upon boot and shoe soles, having, in combination, a roll, means for rotating the roll, means for imparting tipping movements to the roll as it is rotated, a friction pad engaging with the 20 surface of the roll, and a spring-pressed support for the friction pad having a universal connection therewith, substantially as described.

10 10. A machine for operating upon boot and shoe soles, having, in combination, a shaft, an oblique sleeve mounted on the shaft, a roll mounted on the sleeve, connections between the shaft and the roll for rotating the roll, and means for rotating the

sleeve independently of the shaft, substantially as described.

11. A machine for operating upon boot and shoe soles having, in combination, a driving shaft, a tool supported upon the shaft, connections between the shaft and tool to rotate the tool with the shaft, and means for causing the tool to assume different angles of inclination relative to the shaft as it is rotated, substantially as described.

12. A machine for operating upon boot and shoe soles, having, in combination, a shaft, a roll supported upon the shaft, and means for causing the roll when rotated to assume different angles of inclination relative to the shaft, substantially as described.

13. A machine for operating upon boot and shoe soles, having in combination, a substantially cylindrical roll having a periphery arranged to engage with the shoe sole, a supporting shaft for the roll, and means for moving the roll transversely of the axis of the shaft when the roll is rotated, substantially as described.
